THERMOMETER

Elmer C. Hartman, Rochester, N. Y., assignor to
 Taylor Instrument Companies, Rochester, N. Y.,
 a corporation of New York

Application June 29, 1942, Serial No. 449,661

4 Claims. (Cl. 73—374)

This invention relates to thermometers.

The main feature of the invention pertains to a one-piece thermometer of a construction in which the glass front thereof is retained in the thermometer case by a novel bezel arrangement.

The various features of the invention will appear from the detailed description and claims when taken with the drawing in which Fig. 1 is a front view of a thermometer made in accordance with the present invention; Fig. 2 is an enlarged partially vertical section taken substantially on the line 2—2 of Fig. 1; Fig. 3 is a transverse section taken substantially on the line 3—3 of Fig. 1; and Figs. 4 and 5 are vertical sections taken in a plane defined by the bezel receiving groove, showing two different stages of the bezel in the groove.

Referring to the drawing, the thermometer comprises a one-piece case preferably made of die-cast metal, although it will be understood that it may be made of molded rubber or plastic materials, if desired. The case 6 is trough-shaped, as shown particularly in Fig. 3, providing a V-shaped back 7, side walls 8 and end walls 9. A thermometer tube 10 secured in the center of the V-shaped back 7 extends through an opening in the lower end wall 9 (see Fig. 1) into the metal protective bulb 11 joined to the lower end of the case. Suitably graduated scale plates 13 are secured to the back 7 at each side of the thermometer tube 10. The front of the case 6 is closed by a transparent cover plate 14, detachably and resiliently clamped within the case in a manner to be presently described.

By referring to Figs. 2, 4 and 5, it will be noted that the side and end walls 8 and 9 of the case 6 are provided with a groove 15, which preferably extends completely around the inner surface of the case. This groove receives the margin of a bezel serving to lock the glass or cover plate 14 in the case 6. The bezel is preferably made in the form of two complementary L-shaped sections 16, 16 having interfitting ends respectively provided with tongues and recesses which serve to lock the two pieces together when assembled in the groove. Each section comprises a long member 16a and a short member 16b extending at right angles thereto. The short member terminates in a stub 16c which extends generally parallel to the long member 16a with the free ends of the stub and the long member both extending in the same direction. Each section is preferably made from sheet metal having a substantial degree of rigidity. It will be noted that the long member is distorted from a straight

line at point X, so that when unrestrained it occupies the position shown in full lines (Fig. 4), while it occupies the position shown in Fig. 1 when assembled in the thermometer case. It should also be mentioned that the short member has a reduced cross section at point Y, to facilitate flexing this member in the course of assembling the bezel sections into the thermometer case.

10 The outside dimensions of the bezel 16 are greater than interior dimensions of the case so that the outer margin of the bezel, when assembled in the open front of the case, will seat in the groove 15 but the inner dimensions of the 15 bezel are such that its margin will overlie the edge of the glass cover plate 14.

It is essential to retain the cover plate or glass 20 14 in the case without rattling and for this purpose elongated zigzag springs 19 are mounted 25 along the side walls 8 of the case, preferably being spot-welded at points 20 to the flanges 21 of the scale-plate supporting members. The cover plate 14 rests on the crests of these zigzag springs, as shown in Fig. 2, the springs being 30 of such height as to normally maintain the cover plate slightly above the groove 15. Thus, when the bezel 16 is seated in the groove 15 to lock the cover plate in position, the springs 19 will be compressed slightly, thereby resiliently clamping the cover plate between these springs and the inner margin of the bezel (see Fig. 3).

In assembling the thermometer, the glass cover plate 14, which is slightly smaller than the interior dimensions of the open front of the case, is placed 35 within the case so that it rests on the crests of the zigzag springs 19. The cover plate is then pressed down to compress the springs 19 and to expose the continuous groove 15. One bezel section 16 is moved over the surface of the glass cover plate 14 from its dotted position in Fig. 4 until it partially occupies the groove 15 as shown in full lines in the mentioned figure. The second 40 bezel section 16 when inverted, is assembled in the unoccupied portion of groove 15 of the case in the same manner as the first section. In swinging the two sections 16 to the position shown in Fig. 5, the stub end 16c of the left-hand member interlocks with the free end of the long member 16a of the right-hand section and forces the distorted portion of this long member into the groove 15. The spaced ends of the two sections 16 as shown in the upper left hand corner of Fig. 5, are respectively forced in the direction of the arrows until these two ends of the members interlock as 45 shown in Fig. 1. In disassembling the bezel, one 50 55

of the short members 16b for example, the upper one in Fig. 5, is forced upward in the direction of the vertical arrow. The free end of the adjacent long member 16a is moved toward the right, that is, in the direction opposite to that of the horizontal arrow, until the parts occupy the position shown in Fig. 5. In effecting this last-mentioned movement, a tool (not shown) may be inserted in the hole 16d. Thereafter the two bezel sections are removed from the groove 15 by operations which are the reverse of those used during assembly.

I claim:

1. A thermometer comprising a case having a back and side and end walls defining an open front, the inner surface of said side and end walls having bezel-receiving portions therein, a transparent cover plate receivable within said side and end walls for closing the front of said case, and a divided bezel received in said portions to retain said cover plate in said case, said bezel having interlocking ends respectively provided with a tongue and recess whereby it is retained in said portions.

2. A thermometer comprising a case having a back and side and end walls defining an open front, the inner surface of said side and end walls having a groove therein, a transparent cover plate receivable within said side and end walls for closing the front of said case, and a divided rectangular bezel seated in said groove to retain said cover

plate in the case, said bezel having interlocking ends respectively provided with a tongue recess, an end portion of said bezel being normally biased away from said groove.

3. A thermometer comprising a case having a back and side and end walls defining an open front, the inner surface of said side and end walls having a groove therein, a transparent cover plate for closing the front of said case and receivable within said side and end walls, and a rectangular bezel adapted to be seated in said groove, said bezel comprising two substantially similar and somewhat flexible L-shaped sections having means for interengaging the ends of one section with the ends of the other section.

4. A thermometer comprising a case having a back and side and end walls containing an open front, the inner surface of said side and end walls having a groove therein, a transparent cover plate for approximately closing the front of said case and receivable with said side and end walls, and a rectangular bezel adapted to be seated in said groove, said bezel comprising two substantially similar and somewhat flexible L-shaped sections having means for interengaging one section with the ends of the other section, each section having a long member and a short member, at least one member being distorted toward its connected short member in the plane common to said short member.

ELMER C. HARTMAN.
